AUDIO RELAY SYSTEM
 James F. Lawrence, Jr., 465 Sequoia Drive,
 Pasadena, Calif.
 Filed July 13, 1962, Ser. No. 209,673
 11 Claims. (Cl. 317—142)

My invention relates generally to relay systems and, more particularly, to an audio relay system having a delayed relay release following removal of an audio input signal to the system.

In an audio relay system, a relay is normally energized and actuated when an audio input signal is applied to the system. The relay is provided to control external circuits or devices according to the actuation of the relay. The relay, for example, can be used to cause an alarm to operate in the event of failure of a monitored program. In this instance, it is desirable that the relay be immediately actuated when an audio signal is applied to the input of the audio relay system to prevent operation of the alarm and that the relay remain actuated so long as the audio input signal is applied to the system. The relay, however, should not be responsively actuated by false input signals which are not true audio signals of the program. Since there will also exist various gaps in which there is a total absence of an audio input signal due to silent program intervals, the relay should release only after a suitable predetermined time interval which is greater than any of the silent intervals of the program.

For different types of programs, the maximum time interval required before release of the relay will, of course, be different. The release time of the relay should, therefore, be adjustable over a relatively wide range. In certain applications, a consistent release time of the relay following removal of the audio input signal to the audio relay system is also required for precise control of external circuits or devices.

Bearing in mind the foregoing, it is a major object of my invention to provide an audio relay system in which the controlled relay is immediately actuated when an audio input signal is applied to the system, and release time of the relay following removal of the audio input signal is easily adjustable over a wide time range.

Another object of the invention is to provide an audio relay system having a consistently accurate release time of the controlled relay following periodically recurrent removal of the audio input signal to the system, for any particular release time adjustment setting of the system.

A further object of the invention is to provide an audio relay system which is responsively actuated at a very low input signal level but not by false input signals which are not true radio signals of a monitored program, for example.

A still further object of this invention is to provide a relay system which is adjustable to produce a very long delayed relay release following removal of an input signal to the system.

Briefly, and in general terms, the foregoing and other objects are preferably accomplished by providing an audio relay system comprising a combination of an amplifier, a thyratron circuit, a photoconductive time delay control circuit, and a controlled relay. An audio input signal is applied to the amplifier and the amplified signal is used to activate the thyratron circuit. When the thyratron circuit is activated, the controlled relay is immediately actuated and the photoconductive time delay control circuit is energized. The relay remains actuated and relay release is delayed a predetermined length of time following removal of the audio input signal to the system according to the adjustment of the photoconductive time delay control circuit.

2

My invention will be more fully understood, and other objects and advantages of the invention will become apparent, from the following description of an illustrative example of the invention, to be taken in conjunction with the attached drawing, in which:

FIG. 1 is a circuit diagram of a preferred embodiment of an audio relay system;

FIG. 2 is a graph showing curves for relay release time following removal of the audio input signal to the system, as a function of capacitance connection in the photoconductive time delay control circuit of the system; and

FIG. 3 is another graph illustrating a plot of input sensitivity of the system of FIG. 1 as a function of the input signal frequency.

The audio relay system shown in FIG. 1 has an isolated input provided by transformer T1 having a primary winding T1a and a secondary winding T1b. Input terminal L1 is connected to one end of the primary winding T1a, input terminal L2 is connected to the other end through a resistor R1, and input terminal L3 is connected directly to the other end of the primary winding T1a. The resistances of the primary winding T1a and the resistor R1 are each 10K ohms, for example. An audio input signal applied to terminals L1 and L2 will thus see a 20K ohms input which is isolated from ground.

A potentiometer R2 is connected to the secondary winding T1b and the adjustable tap of the potentiometer R2 is connected to the control grid of a triode section V1a of a dual triode V1, as shown in FIG. 1. The cathode of the triode section V1a is connected to ground through a resistor R3, and the anode is connected to a positive supply voltage B+ through resistor R4. The anode of the triode section V1a is connected to the control grid of the other triode section V1b through a coupling capacitor C1. The control grid of the triode section V1b is connected to ground through grid resistor R5 and a capacitor C2 connected in parallel with the resistor R5.

The cathode of the triode section V1b is connected directly to ground, and the anode is connected to a positive supply voltage B+ through load resistor R6. The anode of the triode section V1b is also connected to the control grid of a thyratron V2 through a series combination of coupling capacitor C3 and limiting resistor R7. A resistor R8 connects the common junction of capacitor C3 and resistor R7 to ground.

The cathode of the thyratron V2 is connected to ground through a resistor R9 and also through a series combination including resistor R10 and neon lamp N1. The anode of the thyratron V2 is connected to an A.C. source, and the screen grid is connected to a positive voltage source B+ through a resistor R11. The screen or shield grid of the thyratron V2 is also connected directly to the cathode of the thyratron, as shown in FIG. 1.

The cathode of the thyratron V2 is connected by diode D1 to a common terminal L4, of a series including the terminals L5, L6, L7 and L8, through a small resistor R12 which limits the diode surge current. The cathode of the thyratron V2 is also connected by another diode D2 to the control coil K1a of relay K1 through a filter resistor R13. Filter capacitor C4 connects the diode D2 to ground, as shown. The relay K1 is illustrated as having its pole K1b connected to terminal L9, normally closed contact K1c connected to terminal L10, and normally open contact K1d connected to terminal L11.

Capacitors C5, C6, C7 and C8 are respectively connected to the terminals L5, L6, L7 and L8. The capacitors C5 through C8 are all connected to ground, as shown in FIG. 1. These capacitors each have a different value. For example, the values of capacitors C5, C6, C7 and C8 are respectively 20, 40, 60 and 80 mfd. One or more of the capacitors can be connected in parallel to the ter-

capacitor C7, when the thyratron V2 is cut off as by removal or absence of the audio input signal to the system, the charged voltage on capacitor C7 discharges through the resistors R14 and R15, and the lamp N2 will be extinguished when the capacitor voltage drops below the maintaining voltage for the lamp. The time constant of the discharge circuit is determined by the setting of potentiometer R14 and the capacitance connected at the common terminal L4 so that relay release time is precisely set by the adjustment of potentiometer R14 with the value 10 of the fixed capacitor C7. If it is desired to cause the relay K1 to remain released after drop out has occurred, the audio input signal can be locked out by connecting terminal L3 to L1.

The minimum audio input signal voltage which would 15 fire the thyratron V2 and cause actuation of relay K1 was, for example, .005 volt. The graph of FIG. 3 shows a plot of the minimum input voltage to the preferred system required for relay actuation as a function of the frequency of the input signal or voltage. This minimum input voltage of .005 volt is seen from FIG. 3 to be effective from 20 700 to 2500 c.p.s., approximately. A decrease in sensitivity below 1000 c.p.s. and above 7000 c.p.s. is provided to reduce false triggering from turntable rumble and hum on the low end, and tape and thermal noise on the high 25 end, for example.

If a wider response band is desired, the values of the coupling capacitors C1 and C3 can be increased to lower the low frequency response. High frequency response can be increased by removing the capacitor C2 from the input 30 circuit of the triode section V1b.

It is to be understood that the particular embodiment of my invention described above and shown in the drawing is merely illustrative of and not restrictive on the broad invention and that various changes in design, structure 35 and arrangement may be made without departing from the spirit and scope of the broader of the appended claims.

I claim:

1. A relay system having a delayed relay release, comprising:

a relay including a control coil for actuating said relay when said coil is energized;
a source of power for energizing said coil;
a photosensitive cell for controlling power from said source to said coil, said cell permitting power from said source to energize said coil when said cell is illuminated;
a light-producing device for illuminating said cell, said light-producing device producing a light output and illuminating said cell when said light-producing device is energized;
a capacitor of variable capacitance;
means for connecting said light-producing device to said capacitor;
means for providing a voltage to said capacitor and said light-producing means, said voltage charging said capacitor to an exciting voltage which energizes said light-producing means to illuminate said cell and energize said coil; and
a resistor of variable resistance connected to said capacitor for controlling discharge rate of said capacitor, 55 whereby said light-producing device is maintained energized by said charged capacitor after removal of said voltage for a predetermined length of time according to selected values of said capacitor and resistor, to illuminate said cell and energize said coil to actuate said relay.

2. A relay system having a delayed relay release, comprising:

a relay including a control coil for actuating said relay when said coil is energized;
a first source of power for energizing said coil;

a photoconductive cell for controlling power from said first source to said coil, said cell permitting power from said first source to energize said coil when said cell is illuminated;

a gaseous discharge lamp for illuminating said cell, said lamp producing a light output and illuminating said cell when said lamp is energized;

a capacitor of variable capacitance;

means connecting said lamp to said capacitor;

a second source of power for charging said capacitor to an ionizing voltage which energizes said lamp; switching means operable to connect said second source to said capacitor, to charge said capacitor to said ionizing voltage which energizes said lamp; and

a resistor of variable resistance connected to said capacitor for controlling discharge rate of said capacitor after disconnection of said second source from said capacitor at the end of an operation of said switching means,

whereby said lamp is maintained energized by said charged capacitor after disconnection of said second source for a predetermined length of time according to selected values of said capacitor and resistor, to illuminate said cell and energize said coil to actuate said relay.

3. A relay system having a delayed relay release, comprising:

a relay including a control coil for actuating said relay when said coil is energized;

a first source of power for energizing said coil;

a photosensitive cell for controlling power from said source to said coil, said cell permitting power from said first source to energize said coil when said cell is illuminated;

a light-producing device for illuminating said cell, said light-producing device producing a light output and illuminating said cell when said light-producing device is energized;

a capacitor of variable capacitance;

means for connecting said light-producing device to said capacitor;

a second source of power;

means operable to connect said second source to said coil of said relay and to said capacitor, for directly energizing said coil which actuates said relay and charging said capacitor to an exciting voltage which energizes said light-producing means to illuminate said cell; and

a resistor of variable resistance connected to said capacitor for controlling discharge rate of said capacitor after disconnection of said second source from said capacitor at the end of an operation of said operable means,

whereby said light-producing device is maintained energized by said charged capacitor after disconnection of said second source for a predetermined length of time according to selected values of said capacitor and resistor, to illuminate said cell and energize said coil to actuate said relay.

4. A relay system having a delayed relay release, comprising:

a relay including a control coil for actuating said relay when said coil is energized;

a first source of power for energizing said coil;

a photosensitive cell for controlling power from said source to said coil, said cell permitting power from said first source to energize said coil when said cell is illuminated;

a light-producing device for illuminating said cell, said light-producing device producing a light output and illuminating said cell when said light-producing device is energized;

a capacitor of variable capacitance;

means for connecting said light-producing device to said capacitor;

- a second source of power;
a thyatron connected to said second source and operably energizable to provide an output voltage;
means for applying said thyatron output voltage to said coil of said relay, for directly energizing said coil to actuate said relay; 5
means for applying said thyatron output voltage to said capacitor, for charging said capacitor to an exciting voltage which energizes said light-producing means to illuminate said cell; and 10
a resistor of variable resistance connected to said capacitor for controlling discharge rate of said capacitor after removal of said thyatron output voltage at the end of an operation of said thyatron, 15
whereby said light-producing device is maintained energized by said charged capacitor after removal of said thyatron output voltage for a predetermined length of time according to selected values of said capacitor and resistor, to illuminate said cell and energize said coil to actuate said relay. 20
5. A relay system having a delayed relay release, comprising:
a relay including a control coil for actuating said relay when said coil is energized; 25
a first source of power for energizing said coil;
a photoconductive cell for controlling power from said first source to said coil, said cell permitting power from said first source to energize said coil when said cell is illuminated; 30
a gaseous discharge lamp for illuminating said cell, said lamp producing a light output and illuminating said cell when said lamp is energized;
a capacitor of variable capacitance; 35
a second source of power;
a thyatron connected to said second source and operably energizable to provide an output voltage;
means for applying said thyatron output voltage to said coil of said relay, for directly energizing said coil to actuate said relay; 40
means for applying said thyatron output voltage to said capacitor, for charging said capacitor to an exciting voltage which energizes said light-producing means to illuminate said cell; and 45
a resistor of variable resistance connected to said capacitor for controlling discharge rate of said capacitor after removal of said thyatron output voltage at the end of an operation of said thyatron, 50
whereby said lamp is maintained energized by said charged capacitor after removal of said thyatron output voltage for a predetermined length of time according to selected values of said capacitor and resistor, to illuminate said cell and energize said coil to actuate said relay. 55
6. A relay system having a delayed relay release, comprising:
a relay including a control coil for actuating said relay when said coil is energized; 60
a first source of power for energizing said coil;
a photosensitive cell for controlling power from said source to said coil, said cell permitting power from said first source to energize said coil when said cell is illuminated; 65
a light-producing device for illuminating said cell, said light-producing device producing a light output and illuminating said cell when said light-producing device is energized;
a capacitor of variable capacitance; 70
means for connecting said light-producing device to said capacitor;
a second source of power;
a thyatron connected to said second source and operably energizable to provide an output voltage; 75
a first diode connected to apply said thyatron output voltage to said coil of said relay, for directly energizing said coil to actuate said relay;

- 8
a second diode connected to apply said thyatron output voltage to said capacitor, for charging said capacitor to an exciting voltage which energizes said light-producing means to illuminate said cell; and a resistor of variable resistance connected to said capacitor for controlling discharge rate of said capacitor after removal of said thyatron output voltage at the end of an operation of said thyatron, whereby said light-producing device is maintained energized by said charged capacitor after removal of said thyatron output voltage for a predetermined length of time according to selected values of said capacitor and resistor, to illuminate said cell and energize said coil to actuate said relay. 7. A relay system having a delayed relay release, comprising:
a relay including a control coil for actuating said relay when said coil is energized;
a first source of power for energizing said coil;
a photoconductive cell for controlling power from said first source to said coil, said cell permitting power from said first source to energize said coil when said cell is illuminated;
a gaseous discharge lamp for illuminating said cell, said lamp producing a light output and illuminating said cell when said lamp is energized;
a capacitor of variable capacitance;
a second source of power;
a thyatron connected to said second source and operably energizable to provide an output voltage;
a first diode connected to apply said thyatron output voltage to said coil of said relay, for directly energizing said coil to actuate said relay;
a second diode connected to apply said thyatron output voltage to said capacitor, for charging said capacitor to an exciting voltage which energizes said light-producing means to illuminate said cell; and a resistor of variable resistance connected to said capacitor for controlling discharge rate of said capacitor after removal of said thyatron output voltage at the end of an operation of said thyatron, whereby said lamp is maintained energized by said charged capacitor after removal of said thyatron output voltage for a predetermined length of time according to selected values of said capacitor and resistor, to illuminate said cell and energize said coil to actuate said relay. 8. A relay system having a delayed relay release, comprising:
a relay including a control coil for actuating said relay when said coil is energized;
a first source of power for energizing said coil;
a photosensitive cell for controlling power from said source to said coil, said cell permitting power from said first source to energize said coil when said cell is illuminated;
a light-producing device for illuminating said cell, said light-producing device producing a light output and illuminating said cell when said light-producing device is energized;
a capacitor of variable capacitance;
means for connecting said light-producing device to said capacitor;
a second source of power;
a thyatron connected to said second source and operably energizable to provide an output voltage;
means for applying an input signal to said thyatron, said thyatron being operably energized by at least a predetermined magnitude of said input signal;
means for applying said thyatron output voltage to said coil of said relay, for directly energizing said coil to actuate said relay;
means for applying said thyatron output voltage to said capacitor, for charging said capacitor to an

exciting voltage which energizes said light-producing means to illuminate said cell; and
a resistor of variable resistance connected to said capacitor for controlling discharge rate of said capacitor after removal of said thyratron output voltage at the end of an operation of said thyratron, whereby said light-producing device is maintained energized by said charged capacitor after removal of said thyratron output voltage for a predetermined length of time according to selected values of said capacitor and resistor, to illuminate said cell and energize said coil to actuate said relay. 5

9. A relay system having a delayed relay release, comprising:
a relay including a control coil for actuating said relay when said coil is energized; 15
a first source of power for energizing said coil;
a photoconductive cell for controlling power from said first source to said coil, said cell permitting power from said first source to energize said coil when said cell is illuminated; 20
a gaseous discharge lamp for illuminating said cell, said lamp producing a light output and illuminating said cell when said lamp is energized;
a capacitor of variable capacitance; 25
a second source of power;
a thyratron connected to said second source and operably energizable to provide an output voltage;
means for applying an input signal to said thyratron, said thyratron being operably energized by at least a predetermined magnitude of said input signal; 30
means for applying said thyratron output voltage to said coil of said relay, for directly energizing said coil to actuate said relay;
means for applying said thyratron output voltage to said capacitor, for charging said capacitor to an exciting voltage which energizes said light-producing means to illuminate said cell; and
a resistor of variable resistance connected to said capacitor for controlling discharge rate of said capacitor after removal of said thyratron output voltage at the end of an operation of said thyratron, 40 whereby said lamp is maintained energized by said charged capacitor after removal of said thyratron output voltage for a predetermined length of time according to selected values of said capacitor and resistor, to illuminate said cell and energize said coil to actuate said relay. 45

10. A relay system having a delayed relay release, comprising:
a relay including a control coil for actuating said relay when said coil is energized; 50
a first source of power for energizing said coil;
a photosensitive cell for controlling power from said source to said coil, said cell permitting power from said first source to energize said coil when said cell is illuminated; 55
a light-producing device for illuminating said cell, said light-producing device producing a light output and illuminating said cell when said light-producing device is energized;
a capacitor of variable capacitance; 60
means for connecting said light-producing device to said capacitor;
a second source of power; 65
a thyratron connected to said second source and operably energizable to provide an output voltage;
means for amplifying an input signal and applying the amplified signal to said thyratron, said thyratron be-

ing operably energized by at least a predetermined magnitude of said input signal;
a first diode connected to apply said thyratron output voltage to said coil of said relay, for directly energizing said coil to actuate said relay;
a second diode connected to apply said thyratron output voltage to said capacitor, for charging said capacitor to an exciting voltage which energizes said light-producing means to illuminate said cell; and
a resistor of variable resistance connected to said capacitor for controlling discharge rate of said capacitor after removal of said thyratron output voltage at the end of an operation of said thyratron, whereby said light-producing device is maintained energized by said charged capacitor after removal of said thyratron output voltage for a predetermined length of time according to selected values of said capacitor and resistor, to illuminate said cell and energize said coil to actuate said relay. 10

11. A relay system having a delayed relay release, comprising:
a relay including a control coil for actuating said relay when said coil is energized;
a first source of power for energizing said coil;
a photoconductive cell for controlling power from said first source to said coil, said cell permitting power from said first source to energize said coil when said cell is illuminated;
a gaseous discharge lamp for illuminating said cell, said lamp producing a light output and illuminating said cell when said lamp is energized;
a capacitor of variable capacitance;
a second source of power;
a thyratron connected to said second source and operably energizable to provide an output voltage;
means for amplifying an input signal and applying the amplified signal to said thyratron, said thyratron being operably energized by at least a predetermined magnitude of said input signal;
a first diode connected to apply said thyratron output voltage to said coil of said relay, for directly energizing said coil to actuate said relay;
a second diode connected to apply said thyratron output voltage to said capacitor, for charging said capacitor to an exciting voltage which energizes said light-producing means to illuminate said cell; and
a resistor of variable resistance connected to said capacitor for controlling discharge rate of said capacitor after removal of said thyratron output voltage at the end of an operation of said thyratron, whereby said lamp is maintained energized by said charged capacitor after removal of said thyratron output voltage for a predetermined length of time according to selected values of said capacitor and resistor, to illuminate said cell and energize said coil to actuate said relay. 45
